UNITED STATES PATENT OFFICE.

WILLIS S. SHAFT, OF FARIBAULT, MINNESOTA.

STITCH-DOWN SHOE.

1,088,244.

Specification of Letters Patent. Patented Feb. 24, 1914.

Application filed June 13, 1913. Serial No. 773,526.

To all whom it may concern:

Be it known that I, WILLIS S. SHAFT, a citizen of the United States, residing at Faribault, in the county of Rice and State of Minnesota, have invented certain new and useful Improvements in Stitch-Down Shoes, of which the following is a specification.

My present invention relates to the manufacture of shoes technically known as stitch-down or welt shoes, whereby the uppers are secured to the soles by stitching the former, adjacent the lower margins thereof, to the latter, exteriorly, with the aid of a suitable 15 welt serving as a reinforcement and giving finish to the product.

The principal object of my invention is to provide for the manufacture of shoes of the character described which are strong, 20 durable and inexpensive to manufacture.

Further objects of the invention are to provide a shoe of the character described wherein the lining is more effectually held in place than in the shoes now in common 25 use; to so dispose the lining with respect to the portion of sole that the material adjacent the lower margin of the lining is held in place partly by the weight of the foot as its rests upon the portion of the sole adjacent 30 the foot; and, to construct the portions of the sole with which the lining has engagement of one ply of material thereby avoiding chafing which otherwise might cause the lining to work loose from the sole. 35 The said arrangement and construction of parts will also prevent the squeaking which is caused by the relative movement of the inner sole with respect to the outer sole in shoes where their soles are separable.

Still further objects of my invention are to avoid the use of cement or stitching now used to retain the inner sole in place; and, in general, to facilitate manufacture of shoes of the character described.

Other objects of the invention will appear in the following detailed description taken in connection with the accompanying drawings forming a part of this specification and in which drawings:

Figure 1 is a perspective view of a shoe partly completed according to my invention. Fig. 2 is a transverse section of a last, and the sole, and upper, together with its lining in place about the last. Fig. 3 is a fragmentary perspective view of the sole.

In the drawings, where similar characters refer to similar parts, 4 designates the upper of a shoe which may be of any suitable design and made up of any suitable material, allowance during manufacture being 60 made for turning the material adjacent its lower margin, outwardly, with the object of providing a stitch-down or welt shoe. A lining 5, such as of fabric, is provided within the upper, allowance being made, during 65 manufacture, for the inturning of the lining, adjacent its lower margin, for placing as hereinafter described.

The sole, designated, generally by 6, may or may not be built up of a plurality of 70 plies of leather, one of the principal objects of the invention being to form the sole portion, 7, which is to be disposed adjacent the foot, integral with the sole 8 or a ply thereof, as clearly shown in the drawings. 75

As is clearly shown in Figs. 2 and 3 of the drawings, the sole is channeled as at 9 to form a flap 10 lying within the lateral margin of the sole, or, in other words, having its free end inwardly of the lateral margin 80 of the major portion 8 at a predetermined distance. This channel is preferably of uniform depth and the flap 10 being flexible, permits the sole portion 7 to conform nicely to the periphery of the last 11. The major 85 portion of the sole may be slit as at 12 inwardly from its margins to enable the material adjacent thereto to be turned back and permit ready access to the channel, for 90 a purpose to be subsequently set forth.

In the manufacture of the shoe, the sole 6 is placed, and, if desired, secured upon the last 11 with the sole portion 7 next adjacent thereto, and the sole portion 8 is then turned back to open the channel 9 to permit 95 ready access thereto. The lining 5 is then turned inwardly and doubled upon itself adjacent its lower margin, as clearly shown in Fig. 2 of the drawing so as to lie between in the channel 9. It may be secured in place in any suitable manner, such as by an adhesive or a cord 13 may be drawn tightly between the juxtaposed layers of leather. If desired, both means of securing the lining in place may be resorted to. A toe cap 14, if such is desired, is then placed with its lower portion next adjacent that portion of sole 8 extending beyond the flap 10.

By turning outwardly the material of the 110

upper 4 adjacent its lower margin and placing it next adjacent the said extending portion of sole 8, it may be secured to the sole 6 by stitching 16, a suitable welt 15 being 5 used to reinforce the same and give finish to the shoe.

Trimming and refinements of any suitable sort may be resorted to, in order to place the product in condition for the 10 market.

From the foregoing it is made manifest that I have improved the manufacture of stitch down shoes, enabling them to be manufactured at a comparatively low cost consistent with the desideratum, durability and efficiency. The product is shapely, easy to wear in that the inner sole conforms, at the start, to a portion of the periphery of the last and all movement of the lining adjacent 15 the inner sole, and movement of said sole relative to the outer sole is avoided.

I claim:—

1. In a stitch-down shoe, the combination of a sole having its marginal portion channeled to provide an upper flap, the marginal edge of said upper flap lying within the marginal edge of said sole, a lining having its lower marginal portion folded upon itself and lying within said channel, and 20 means for securing said marginal portion of said lining in said channel.

2. In a stitch-down shoe, the combination of a sole having its marginal portion channeled to provide an upper flap, the marginal edge of said upper flap lying within the marginal edge of said sole, a lining having its lower marginal portion folded upon itself and lying within said channel, and a cord drawn tightly within the said fold of 35 said lining for securing the same in place.

3. In a stitch-down shoe, the combination of a sole having its marginal portion channeled to provide an upper flap, the marginal edge of said upper flap lying within the marginal edge of said sole, a lining having its lower marginal portion folded upon itself and lying within said channel with the lower marginal edge of said lining exterior 45 of the space inclosed by the major portion of the lining, and a cord drawn tightly 50

within the said fold of said lining for securing the same in place.

4. In a stitch-down shoe, the combination of a sole having its marginal portion channeled to provide an upper flap, the marginal edge of said upper flap lying within the marginal edge of said sole, a lining having its lower marginal portion folded upon itself and lying within said channel, means for securing said marginal portion of said lining in said channel, an upper having its lower marginal portion turned outwardly, and means for securing said outturned portion of said upper to said sole outwardly of the said upper flap. 55 60 65

5. In a stitch-down shoe, the combination of a sole having its marginal portion channeled to provide an upper flap, the marginal edge of said upper flap lying within the marginal edge of said sole, a lining having its lower marginal portion folded upon itself and lying within said channel with the lower marginal edge of said lining exterior of the space inclosed by the major portion of the lining, a cord drawn tightly 70 75 within the said fold of said lining for securing the same in place, an upper having its lower marginal portion turned outwardly, and means for securing said outturned portion of said upper to the said sole 80 outwardly of the said upper flap. 85

6. In a stitch-down shoe, the combination of a sole having its marginal portion channeled to provide an upper flap, the marginal edge of said upper flap lying within the marginal edge of said sole, a lining having its lower marginal portion lying within said channel, means for securing said marginal portion of said lining in said channel, an upper having its lower marginal portion turned outwardly, and means for securing said outturned portion of said upper to said sole outwardly of the said upper flap. 90 95

In testimony whereof I affix my signature in presence of two witnesses.

WILLIS S. SHAFT.
